INVENTOR

UNITED STATES PATENT OFFICE.

ALEXANDER D. PENFOLD, OF RIDGEWOOD, NEW JERSEY, ASSIGNOR TO
E. J. BROOKS & CO., OF NEW YORK, N. Y.

LABEL-HOLDER FOR FREIGHT-CARS.

SPECIFICATION forming part of Letters Patent No. 276,980, dated May 1, 1883.

Application filed December 9, 1882. (No model.)

To all whom it may concern:

Be it known that I, ALEXANDER D. PENFOLD, a citizen of the United States, residing at Ridgewood, Bergen county, in the State of New Jersey, have invented a new and useful Improvement in Label-Holders for Freight-Cars, of which the following is a specification.

This invention relates to improvements in that class of devices commonly known by railway men as "car-card racks," and consisting, generically, of permanent attachments to the sides of railway freight-cars as means for holding and displaying "destination-cards" and other "car-cards" used for labeling such cars to show their destination, contents, and the like, without nailing on such labeling-cards. The devices are herein termed "label-holders," in accordance with the official classification of patents.

The present invention consists in certain novel combinations of peculiarly constructed and arranged parts, hereinafter set forth and claimed, whereby I aim to accomplish the following objects, viz: first, to securely attach the paper car-cards or labeling-cards generally used without the aid of puncturing-points, which are liable to tear the hands, and by a simple device more easily manipulated than any heretofore used; second, to provide by the same means, in part, for securely holding car-cards, or substitutes for car-cards in the form of tags, so that the latter may be conveniently used on lines communicating with those which use the paper cards; third, to mask the spring or springs forming part of the device, and by the same means to limit the opening movement to prevent accidentally leaving the holder open, and to re-enforce the attaching devices and preclude the escape of loose cards at the lower edge of the holder, as hereinafter more fully set forth.

Two sheets of drawings accompany this specification as part thereof, illustrating respectively a preferred form of holder and a modification thereof, and the use of either holder for attaching paper car-cards and for holding the said "tin-tags."

Figure 1 is a small face view of said preferred holder, and Fig. 2 is an edge view thereof on the same scale, showing it by full and dotted lines in its respective conditions—closed

and open. Fig. 3 is a sectional face view of a portion of the lower edge of this holder. Fig. 4 is a vertical section on the line 4 4, Fig. 3. Fig. 5 is a top view of a portion of the spring-case of this holder, and Fig. 6 is a top view of its "rim," stripped, on a larger scale, showing its construction. Fig. 7 is a half face view, on a like large scale, of a holder of modified construction. Fig. 8 is a vertical section thereof. Fig. 9 is a face view of a central portion of the lower edge of this holder, showing its arrangement of springs more fully; and Fig. 10 is a top view of its rim, stripped.

Like letters of reference indicate corresponding parts in all the figures.

In either form my "holder" comprises a rim, R, of stiff wire, provided with an elastic netting, N, of finer wire, crimped to form numerous bearing-points and render the netting very elastic, and so attached to the back of the rim as to press against the side S of a railway freight-car, or any interposed labeling-card, C, or tag T of any description, when said rim is pressed against the said side of the car in the "closed" condition of the holder, as represented by full lines in Fig. 2, and by Figs. 4 and 8. The holder is so closed and held against the side of the car by means of spiral hinge-springs H, a pair preferably as shown, which surround an outer cross-bar of said rim R at the lower edge of the holder, with their inner ends, z, applied to an inner cross-bar of said rim R parallel with the former, and to which the lower edge of the netting N is attached, while the outer ends, y, of the springs are attached by wood-screws x (or it may be by bolts) to the side of the car. A pair of short light hinge-springs are represented at H in Figs. 3 and 4, applied near the respective lateral edges of the holder. A pair of longer and heavier hinge-springs, H H, extending to mid-width of the holder from its respective lateral edges, with their inner ends curved backwardly to form a peculiarly-strong connection with said inner cross-bar, are represented in Figs. 7, 8, and 9. Such details form no part of my present invention. The said rim R in each form is, moreover, constructed with an outward bend or horizontal "arch," a, in its upper horizontal portion, and said arch is constructed or provided with a stud or studs, b b, preferably a pair as shown, matching the

suspending-holes *c*, Fig. 7, in the tags aforesaid, one of which is represented at *T* in Fig. 7. With the aid of this construction the holder in either of its forms is adapted to hold equally well a labeling-card, *C*, Fig. 1, of paper, or a suspended tag, *T*, Fig. 7, as aforesaid, which ever may be in use by the shipping company or line. As shown in Figs. 1, 2, and 6, said studs *b* are integral with the wire rim, being readily formed by bends, as shown. In Figs. 7, 8, and 10 I have shown them as formed on collars embracing the rim-wire. Either form or any approved construction of such studs may be employed. In said preferred form a spring case or mask, *M*, preferably a light malleable-iron casting, which may be of the shape clearly shown by Figs. 3 to 5, is attached by screws to the side of the car, so as to inclose and conceal the said hinge-spring, said mask having stop-notches *n*, matching those portions of the rim *R* which form the lateral edges of the holder, and additional notches, *o*, to receive what may be termed the "shanks" of the said inner ends, *z*, of the hinge-springs *H*. Said notches *n* limit the opening motion of the holder, (illustrated by dotted line in Fig. 2,) to the extent indicated, or thereabout, so as to facilitate placing cards or tags therein, and to preclude leaving the holder open accidentally, by stopping it within the closing scope of the springs, and the latter may consequently be shorter and lighter than would otherwise be required. Said mask *M* serves also to re-enforce the hinge-

springs *H* and their screws as attaching devices, and to preclude the escape of loose cards at the lower edge of the holder. A central staple, *s*, is shown in Figs. 7, 8, and 9 as an illustrative substitute device for use in cheaper forms made without the said mask.

Having thus set forth my said invention, I claim as new and desire to patent under this specification—

1. A label-holder for freight-cars, having an elastic netting, *N*, of crimped wire, supported by a stiff rim, *R*, which is provided at its lower edge with hinge-springs *H*, the latter being adapted to be attached to the side of a car, and to press said netting against a label introduced behind it, substantially as herein set forth.

2. A label-holder for freight-cars, having an elastic netting, *N*, supported by a stiff rim, *R*, the latter constructed with an arch, *a*, in its upper portion, provided with a stud or studs, *b*, for suspending a tag behind said netting, substantially as herein set forth.

3. In combination with the hinge-springs *H*, arranged at the lower edge of the label-holder, and the rim *R*, provided with an elastic netting, *N*, the spring case or mask *M*, inclosing said springs, and having stop-notches *n* to limit the opening of the holder, substantially as herein set forth.

ALEXANDER D. PENFOLD.
